UNITED STATES PATENT OFFICE.

JOSEPH SMITH, EPHRAIM CHABOT, AND JOSEPH CHABOT, OF PROVIDENCE,
RHODE ISLAND.

DESIGN FOR A BASE FOR STOVE-LEGS.

SPECIFICATION forming part of Design No. 33,888, dated January 8, 1901.

Application filed December 13, 1900. Serial No. 39,797. Term of patent 7 years.

To all whom it may concern:

Be it known that we, JOSEPH SMITH, EPHRAIM CHABOT, and JOSEPH CHABOT, residing in the city and county of Providence, in the State of Rhode Island, have invented a new and original Design for a Base for Stove-Legs; and we do hereby declare that the following is a full, clear, and exact description thereof, reference being had to the accompanying drawings, and to the letters of reference marked thereon, which form a part of this specification.

Figure 1 represents a top view of our design. Fig. 2 shows a vertical cross-section taken on line 2 2 in Fig. 1.

The leading feature of our design consists of a circular plate A, a large portion of which is raised to make a circular curved border C,

forming a circular groove or chamber D in the under side of the plate beneath said border. A circular opening J is made in the center of the plate, slightly flaring upward.

Having thus described our invention, what we claim as new, and desire to secure by Letters Patent, is—

The design for a base for a stove-leg, as shown and described.

In testimony whereof we have signed our names to this specification in the presence of two subscribing witnesses.

JOSEPH SMITH.
EPHRAIM CHABOT.
JOSEPH CHABOT.
